UNITED STATES PATENT OFFICE.

CONRAD DRESSLER, OF CLEVELAND, OHIO, ASSIGNOR TO AMERICAN DRESSLER TUNNEL KILNS, INC., OF NEW YORK, N. Y., A CORPORATION OF NEW YORK.

CONTINUOUS KILN AND METHOD OF OPERATING SAME.

Continuation of application Serial No. 399,296, filed July 27, 1920, renewed April 24, 1923. This application filed August 29, 1924. Serial No. 734,859.

To all whom it may concern:

Be it known that I, CONRAD DRESSLER, a subject of the King of Great Britain, and resident of Cleveland, in the county of Cuyahoga and State of Ohio, have invented certain new and useful Improvements in Continuous Kilns and Methods of Operating Same, of which the following is a specification.

The general object of the present invention is to provide for the effective utilization of a continuous tunnel kiln in heating articles to a uniform temperature where the rate at which heat should be imparted to the articles varies from time to time.

My invention was primarily devised for, and is of a special value in a plant for casting and rolling aluminum. In rolling aluminum it is desirable that the billets should be delivered to the rolls at a temperature of about 500° C. If heated above this temperature the billets approach too closely to the melting point of aluminum, and when appreciably below this temperature, aluminum does not have the proper ductility. The billets are formed by casting, and may be taken out of the moulds while their interiors are well above 500° C., although their surface temperatures will then be less than 500° C. In such case, while a billet may contain sufficient heat to bring it to an average temperature of 500° C., it is necessary to place the billet in an annealing furnace or soaking pit in which the billet temperature is made uniform from surface to center before passing the billet to the roll.

If each billet cast should be withdrawn from the mould in which it is formed and placed in the annealing kiln or soaking pit, while still retaining heat sufficient to bring the entire billet to the desired temperature for rolling it would not be necessary to use any fuel in heating the furnace or soaking pit except perhaps to make up for some or all of the heat radiation or other losses from the furnace or pit. Where the billets are annealed in a continuous tunnel kiln it is not practically possible, however, to put all of the billets into the kiln while each billet still retains sufficient heat to bring the billet to the desired temperature for rolling. In the operation of a continuous tun-

nel kiln the billets must be fed into the entrance end of the kiln at the same rate as they are withdrawn from the exit end of the kiln. The billets must be passed immediately to the rolls as they are withdrawn from the kiln to avoid cooling, and the rate at which the billets are fed into the entrance end of the kiln thus depends upon the rate at which the billets are passed through the rolls. The exigencies of plant operation make it impossible from a practical standpoint to continuously cast billets at the same rate as the billets are rolled. In some plants there may be periods in which the casting rate and the rolling rate are approximately the same but as a rule, the rate of casting will be either in excess of or below the rate of rolling.

A specific object of the present invention is to provide a continuous tunnel kiln construction and mode of operation whereby billets may be properly annealed at the desired temperature of, say 500° C., as fast or as slowly as is necessary to provide billets for the rolls when the operation of the latter is irregular or intermittent, as well as when it is regular and continuous, and which will effectively utilize the available heat contained in the billets fed into the kiln.

In the practical carrying out of my invention I employ a continuous tunnel kiln of the muffled heated type, and preferably a kiln of the well known Dressler type having internal combustion chambers for heating the kiln, and provisions for maintaining a directed gravity circulation of the kiln atmosphere, and supply heat to or, if necessary, abstract it from the kiln as required to bring the billets to the desired temperature in their passage therethrough regardless of the rate at which the billets are passing through the kiln or of the amounts of heat retained by the different billets when introduced into the kiln. In the preferred mode of accomplishing this, I pass a stream of air through the kiln chamber from its entrance end to its exit end and then return this air to the entrance end of the kiln through the muffles or internal combustion chambers wherein it is utilized so far as may be required to support the combustion of fuel fed into the muf-

ties or combustion chamber. The amounts of air thus passing through the kiln and combustion chamber and of fuel supplied to the combustion chamber are preferably regulated as required to maintain an approximately constant annealing temperature of say 500° C., in a portion of the kiln adjacent its delivery end and to bring each billet to a temperature which approximates the annealing temperature during its passage through the portion of the kiln chamber preceding that in which the constant annealing temperature is maintained. When it is necessary to supply heat to the kiln in order to bring the billets to the desired temperature for rolling and to make up for heat lost from the kiln, it is only necessary to pass through the kiln chamber sufficient air to support the proper combustion of the fuel burned in the combustion chambers or muffles of the kiln, and the supply of air to the entrance end of the kiln, should then be proportioned to the rate of fuel combustion. During any period, however, in which the billets passed into the entrance end of the kiln retain more heat than is required to bring the billets to the desired final temperature and to make up for the heat lost from the kiln, the air serves to abstract from the kiln the excess heat supplied by the billets, and the amount of air then supplied must be proportioned to the amount of such excess heat. In any event the gas consumption is at a practical minimum.

35 The various features of novelty which characterize my invention are pointed out with particularity in the claims annexed to and forming a part of this specification; but for a better understanding of the invention and the advantages possessed by it reference should be had to the accompanying drawings and descriptive matter in which I have illustrated and described a preferred embodiment of the invention.

40 45 Of the drawings:

Fig. 1 is a somewhat diagrammatic sectional elevation;

Fig. 2 is a transverse section on the line 2—2 of Fig. 1;

50 Fig. 3 is a view taken similarly to Fig. 1 showing a modification; and

Fig. 4 is a plan of a portion of the apparatus shown in Fig. 3.

55 The kiln shown in the drawings comprises an elongated kiln chamber A, provided at its entrance end with an ante chamber A' having a door B between it and the kiln chamber and an inlet door B' at one side. At the opposite end of the kiln chamber is an exit chamber A'' with doors C and C' at its opposite ends. The billets X are moved through the kiln on cars D which may be of the type commonly employed in moving ware through tunnel kilns. As shown the cars are each provided with a frame work D' for supporting a plurality of spaced apart billets X. The cars are inserted one at a time at the entrance end of the kiln, and the train of cars normally filling the kiln is advanced a car length each time a car is inserted, by the car pusher M which may be of any usual or suitable type employed for the purpose. It will be understood, of course, that each time a car is moved into the kiln from the ante chamber A' a car is moved from the kiln into the exit chamber A''. The kiln shown is formed with benches A³ at the opposite sides of the pathway for the cars and on these benches are located the combustion chambers F. Each combustion chamber extends from the exit end of the kiln for a considerable distance, say half or two thirds of the length of the kiln, toward the entrance end of the kiln, where it is connected to a corresponding header H'. The latter is connected to the ends of pipes H running to the entrance end of the kiln where they are connected to a corresponding header H². Fuel as for instance, combustible gas, is supplied to each combustion chamber adjacent its exit end at one or more points as by the inlet or burner pipes G of which two, one for each combustion chamber, are shown. Air is admitted to the same end of each combustion chamber from the interior of the kiln through an inlet passage F³ formed in the masonry F² closing the corresponding end of the combustion chamber. Preferably the walls of each combustion chamber are formed with channels F' extending transversely to the length of the combustion chamber and opening to the kiln chamber at the top and the bottom of the combustion chamber as set forth in my prior Patent No. 1,170,428. These channels insure a directed gravity circulation of the kiln atmosphere transversely of the length of the kiln and tending to equalize the temperature conditions at different levels in the portion of the kiln chamber traversed by the goods.

60 Each header H² is provided with an outlet H³ formed in the bench and communicating through a tunnel I with a suitable suction device, such as the stack I' shown, for creating a draft through the combustion chambers. A damper J regulates the stack suction impressed on the headers H². Air is supplied as required to the kiln chamber at its entrance end. Advantageously this air passes through the air discharge box K which is located and shaped to discharge the air in a film like stream flowing along the roof of the kiln chamber toward the exit end of the latter. As shown, the discharge duct K is supplied with air by a fan L connected to the duct K by a pipe L' and the amount of air supplied may be regulated by a damper L² in the pipe L, but the air supplied need not be under pres-

sure in all cases and the kiln may be heated in other ways than that shown, as by electricity.

In the preferred mode of operation contemplated a portion of the kiln chamber adjacent its delivery end is maintained at, or approximately at the desired annealing temperature, and heat is supplied to or abstracted from the preceding portion of the kiln chamber as required to bring each of the billets approximately to the annealing temperature during its passage through the initial portion of the kiln. It will be apparent, in view of the explanations made above, that when billets containing considerable casting heat are being inserted into the kiln, the first effect of the air admitted to the kiln through the duct K is to cool the billets, but as this air and the billets travel toward the exit end of the kiln they receive heat from the combustion chambers and the pipe extensions H thereof and the apparatus should be so operated that a zone of approximately constant temperature which is that at which the billets are to be delivered is maintained adjacent the exit end of the kiln. When, as may sometimes happen, the hot billets contain more than the necessary heat required to bring them to a uniform delivery temperature no gas need be supplied to the combustion chambers and in this case excess heat introduced into the kiln by the billets and not lost by radiation from the kiln walls is carried out of the kiln through the stack I'. Under other conditions gas is burnt in the combustion chambers at the rate required to make up for radiation losses and for the small loss of heat carried out of the kiln through the stack I'. Under other conditions gas is burnt in the combustion chambers at the rate required to make up for radiation losses and for the small loss of heat carried out of the kiln through the stack and that required to bring the billets up to the delivery temperature.

In cases in which it is necessary or desirable to anneal the metal in an atmosphere which is neutral or at least not highly oxidizing, such as an atmosphere of nitrogen, carbon monoxide or carbon dioxide, some modification of the apparatus shown in Figs. 1 and 2 must be employed. One simple modification for use under such conditions is illustrated in Figs. 3 and 4. In this modification, the groups of pipes H are arranged to take up less space, measured transversely of the kiln, than the construction shown in Figs. 1 and 2. Alongside of each group of tubes H is a second group of tubes HC connected at their ends to headers HB' and HB² respectively. The header HB' receives air, as from the fan L, through the pipes Q', and the header HB² connects to one end of a duct HD in the corresponding kiln bench

which runs under the corresponding combustion chamber for its full length, being connected to the latter at the exit end of the kiln by a port F¹⁰. The headers HA' and HA² to which the pipes H are connected are arranged and connected as are the headers H' and H² of the construction first described. A pipe provided with a controlling valve P' leads to the kiln chamber from a gas tank P or other suitable source of supply of the neutral or non-oxidizing gas which is to form the atmosphere of the kiln chamber. As shown, the pipe P discharges into the kiln chamber through a nozzle KA like the nozzle K first described.

It will be apparent to those skilled in the art that my invention may be carried out by means of other forms of kiln than the preferred construction shown herein and that my invention is capable of advantageous use for other purposes than preparing aluminum billets for rolling.

This application is a continuation of the application No. 399,295, filed July 27, 1920, and renewed April 24, 1923.

Having now described my invention, what I claim as new and desire to secure by Letters Patent, is;

1. The method of annealing articles previously heated to different temperatures which consists in passing the articles through an elongated annealing chamber and supplying heat to, or abstracting it from the chamber as required to maintain the desired annealing temperature in a final portion of the kiln and to bring each article to a temperature approximately the same as said desired temperature during the passage of the article through the preceding portion of the chamber.

2. The method of annealing articles heated to different temperatures which consists in passing the articles through an elongated annealing chamber and supplying heat to, or abstracting it from the kiln as required to maintain each article at a desired annealing temperature during its passage through a final portion of the chamber and to bring the article to a temperature approximately the same as the annealing temperature during the passage of the article through the preceding portion of the chamber.

3. The method of utilizing the available casting heat retained by cast billets in annealing the billets at a rate varying at times from the rate at which the billets are cast, which consists in passing the billets through an elongated annealing chamber and supplying heat to, or abstracting it from the chamber as required to maintain each billet at an approximately constant annealing temperature during a final portion of its travel through the chamber, notwithstanding the variations in casting heat retained by the billets when entered in the chamber, and

variations in the speed at which the billets are moved through the chamber.

4. The method of supplying a variable demand for annealed billets cast at a rate varying at times from the rate at which the annealed billets are required, which consists in passing the billets in a continuous stream through an elongated annealing chamber at a rate of travel varying with the demand for 5 annealed billets, and supplying heat to, or abstracting it from the chamber as required to maintain each billet at an approximately constant annealing temperature during a final portion of its travel through the chamber, notwithstanding variations in the amount of casting heat retained by the billets when entered in the chamber and the varying speeds at which the billets are moved through the chamber.
- 10 5. The method of operating a continuous tunnel kiln comprising an elongated kiln chamber and a combustion chamber therein extending from the exit end of the kiln chamber towards its inlet end which consists 15 in passing air through the kiln chamber from its inlet end to its exit end, and from the kiln chamber into the combustion chamber at the exit end of the kiln chamber and supplying fuel to the combustion chamber at its 20 exit end as required to maintain a uniform temperature in a portion of the kiln chamber adjacent its exit end.
- 25 6. The method of annealing billets at a desired temperature and utilizing casting heat in so doing, which consists in passing the billets through a tunnel kiln chamber, heating said chamber by an internal combustion chamber located in the kiln chamber and extending from the exit end toward the

entrance end of the kiln chamber, and passing air through the kiln chamber from its entrance end towards its exit end and thence into and through the combustion chamber, and supplying fuel to the combustion chamber adjacent the exit end of the kiln as required to maintain a portion of the kiln chamber adjacent its exit end at said desired temperature.

7. A continuous tunnel kiln comprising in combination an elongated kiln chamber, a combustion chamber extending lengthwise of the kiln from the delivery end of the latter toward its entrance end, means supplying fuel to said combustion chamber at the delivery end of the kiln, an air inlet to the combustion chamber from the kiln chamber at the delivery end of the latter, and means for passing air into the kiln chamber at its entrance end.

8. A continuous tunnel kiln comprising in combination with an elongated chamber, a combustion chamber extending lengthwise of the kiln from the delivery end of the latter toward its entrance end, means supplying fuel to said combustion chamber at the delivery end of the kiln, and means for supplying air to said combustion chamber at the delivery end of the kiln including provisions for causing the air so supplied to travel longitudinally of the kiln chamber from the entrance end to the delivery end thereof and to abstract heat from the kiln chamber in its travel.

Signed at Cleveland, in the county of Cuyahoga, and State of Ohio, this 25th day of August, A. D. 1924.

CONRAD DRESSLER
